TOY

Charles H. Rayburne, Portland, Oreg.

Application April 9, 1945, Serial No. 587,289

3 Claims. (Cl. 46—91)

This invention relates to toys and it is one object of the invention to provide a toy including a container which is preferably in the form of a glass bottle and has therein a miniature submarine or other aquatic object floating in water, there being provided means for causing the object to have diving movements imparted to it.

Another object of the invention is to provide the bottle with a neck in which is mounted an expandable and contractable member which may be gradually extended and retracted and thereby vary pressure upon the water and cause the object to have diving movements.

Another object of the invention is to so form the pressure applying means that it may be actuated by a rod disposed vertically in the bottle neck and protrude upwardly therefrom so that its upper end may be grasped and the rod moved longitudinally of the neck.

Another object of the invention is to provide a pressure applying means which may be easily and quickly applied to or removed from the neck of a bottle and form an air-tight seal for the upper end of the bottle neck as well as constituting means for varying pressure upon the water in the bottle.

Another object of the invention is to provide a toy which is very attractive and capable of being manufactured at small cost.

In the accompanying drawings:

Fig. 1 is a view showing the toy partially in vertical section and partially in side elevation.

Fig. 2 is a sectional view on an enlarged scale, taken longitudinally through the neck of the bottle and the pressure applying means.

Fig. 3 is a sectional view taken transversely through the neck and the pressure applying means on the line 3—3 of Fig. 2.

This toy includes a container 1 which is transparent and preferably consists of a glass bottle, such as a large jug, and has a neck 2 of appropriate length and diameter. This neck has its upper end portion externally threaded for engagement by a cap 3 which is formed of metal and threaded so that it may be screwed tightly upon the neck. At its center, the cap is formed with an opening surrounded by a short upstanding neck 4 and within the cap is a sealing disc 5 for forming an air and water-tight closure for the upper end of the neck 2 when the cap is screwed tightly into place. Before the upper end of the neck 2 is closed the container or bottle 1 is filled with water, as shown in Fig. 1. After the bottle has been filled with water, an object 6 which may be a miniature submarine, fish,

mermaid or the like, is placed in the bottle and normally floats upon the surface of the water. The object is preferably formed of wood and has its bottom portion coated with a chemical mixture consisting of sesquisulfide of phosphorus (white phosphorus) and a binder, such as gum arabic, the binder being one-third to one-fifth of the mixture. After the phosphorus has been applied to the bottom of the object, a coating of shellac is applied. While one object has been shown in the bottle, in the present illustration, it will be understood that additional objects may be provided, according to the size of the bottle.

During use of the toy, the object is to be caused 15 to either float upon the water or having diving movements imparted to it toward the bottom of the bottle and back to the surface of the water. To effect these diving movements, there has been provided pressure controlling means mounted in 20 the bottle neck 2. This pressure controlling means has an elastic thimble 7 formed of rubber and may be referred to as a rubber bag if desired. The thimble has a rounded or hemispherical bottom 8 and its upper end is open and surrounded 25 by an outstanding annular flange 9 which is of such width that when the flange is resting upon the upper end of the bottle neck, its outer marginal edge is flush with the outer surface of the neck. The sealing disc rests upon the upper 30 surface of this flange and, when the cap is tightened, pressure is applied to compress the flange and form a very tight seal.

The rubber thimble is to be extended longitudinally of the neck into the bottle and, to accomplish this, there has been provided a cylindrical expander 10 which is formed of metal and has a rounded bottom 11 formed with a depression 12 at its center to provide a seat for the lower 35 end of an actuating rod 13. A metal sleeve 14 fits snugly within the upper portion of the rubber nipple and has telescoping engagement with the expander 10 so that the expander may be shifted longitudinally in the sleeve. At its upper end, the sleeve carries a metal disc or washer 15 welded 40 to the sleeve, and this disc is formed with a threaded opening through which the threaded upper portion of the rod 13 is engaged. The rod projects upwardly through the sealing disc 5 and the neck 4 of the cap 3 and, at its upper 45 end, carries a hand hold 16 which may be a cross head or a hand wheel. When this hand hold is grasped the rod may be easily turned and, as the rod is moved downwardly, its lower end, which engages in the seal 12, will force the expander 50 to the bottom of the neck and cause the rubber nipple to be

extended downwardly in the bottle 1. As the expander and the nipple move downwardly, pressure will be gradually increased in the bottle and this increase of pressure will cause air in pores of wood from which the object 6 is formed will be compressed and the object will gradually move downwardly in the water. The weight of the phosphorus tends to carry the object downwardly when the air is compressed. Downward movement of the object may be continued to the bottom of the bottle or stopped at any depth desired. When it is desired by proper adjustment of the rod 13 to have the object move toward and eventually return to the surface of the water, it is merely necessary to turn the rod 13 in a raising direction and, as the rod moves upwardly, the nipple 7 will contract and carry the expander upwardly with it. The pressure upon the air in the object will thus be gradually reduced and the object will move upwardly until it reaches the surface of the water. It will thus be seen that a person operating the toy may manually control the movements of the object and cause it to have diving movements in the water. Most glass jars will break at a pressure of about 14 pounds, but as only 2 to 6 pounds pressure is necessary to cause downward movement of the object to the bottom of the jar there is no danger of breaking the jar.

What is claimed is:

1. A toy comprising a transparent container having a neck at its upper end, liquid in said container, an object in said container adapted to float upon and move vertically through the liquid, said object being formed of wood and coated with phosphorus, a closure for the upper end of the neck, and means associated with said closure and operating through said neck for progressively varying pressure upon the liquid and thereby causing said object to execute diving movements through the liquid.

2. A toy comprising a transparent container having a neck at its upper end, liquid in said container, an object in said container adapted to float upon and move through the liquid, said object being coated with phosphorus, a cap detachably applied to said neck, a disc in said cap, a rubber thimble fitting snugly in said neck and closed at its lower end, an outstanding flange about the upper end of said thimble gripped between the disc and the upper end of said neck, and means operating through the cap and disc and associated with said thimble for extending and retracting the thimble and thereby exerting varying pressure upon the liquid to cause said object to execute diving movements through the liquid.

3. A toy comprising a transparent container having a neck at its upper end, liquid in said container, an object in said container adapted to float upon and move through the liquid, a portion of the object being coated with a mixture of white phosphorus and a binder, a cap detachably applied to said neck, a disc in said cap, a rubber thimble fitting snugly in said neck and closed at its lower end, an outstanding flange about the upper end of said thimble gripped between the disc and the upper end of said neck, an expander in said thimble having a closed bottom resting upon the bottom of said thimble and open at its top, a sleeve in the upper portion of said thimble in telescoping engagement with the expander, a threaded actuating rod passing through the cap and sealing disc and extending longitudinally of the neck with its lower end bearing against the bottom of said expander, and means for turning said rod and shifting the rod longitudinally to effect expansion and contraction of said nipple to cause said object to execute diving movements through the liquid.

CHARLES H. RAYBURN.
